UNITED STATES PATENT OFFICE.

RUPERT E. RUNDELL, OF ROCKVILLE CENTER, NEW YORK, ASSIGNOR TO INTERNATIONAL CIGAR MACHINERY COMPANY, A CORPORATION OF NEW JERSEY.

SELF-FEEDING CIGAR-BUNCH SHAPER.

Application filed December 22, 1923. Serial No. 682,173.

To all whom it may concern:

Be it known that I, RUPERT E. RUNDELL, a citizen of the United States, residing at Rockville Center, county of Nassau, and State of New York, have invented a new and useful Improvement in Self-Feeding Cigar-Bunch Shapers, of which the following is a specification.

This invention relates to a self-feeding cigar bunch shaper; and it has for its main object the production of a device in which a cigar bunch is moved or fed to shaping position, there shaped, and then removed from said shaping position. With this and other objects not specifically mentioned in view, the invention consists in certain constructions and combinations which will be herein-after fully described and then specifically set forth in the claims hereunto appended.

In the accompanying drawings, which form a part of this specification and in which like characters of reference indicate the same or like parts, Fig. 1 is a sectional elevation of a device constructed in accordance with the invention; Fig. 2 is a similar view showing the parts in different relation; Fig. 3 is a side elevation of the structure shown in Fig. 1, with its cam-operated connections; Fig. 4 is a plan view of the device shown in Fig. 1; Fig. 5 is a fragmentary perspective view of a cigar bunch and the shaping dies used in the device shown in Fig. 1; and Fig. 6 is a fragmentary view of a part of a cigar bunch and one pair of said dies shown in shaping relation.

In carrying the invention into effect, there is provided means for feeding a cigar bunch to shaping position or bunch carrying means, and bunch compressing means operative to shape one or both ends of the cigar bunch so positioned, a part of the compressing means being embodied in the carrying means. In the best constructions, the bunch carrying means engages the mid-section of the cigar bunch, and the bunch compressing means engages the ends of the bunch. The said means may be widely varied in construction within the scope of the claims, for the particular device selected to illustrate the invention is but one of many possible concrete embodiments of the same. The invention, therefore, is not to be restricted to the precise details of the structure shown and described.

Referring to the drawings, there is provided a support 7 in which, or on which, the

active parts of the device are mounted. This support is adapted to be mounted upon the bed of a cigar machine in connection with which it is used. The support 7 is provided with two parallel slideways, a long one marked 8 and a shorter one marked 9. Mounted to reciprocate in the slideway 8 is a long slide 10. Mounted to reciprocate in the slideway 9 is a shorter slide 11. The slide 10 is provided with a rack 12 and the slide 11 is provided with a rack 13, these two racks being in mesh with a pinion 14 mounted on a squared end 15 of a short shaft 16 journaled in a suitable bearing in the support 7. The shaft 16 projects to the rear of the support 7 and upon its projecting end is secured an arm 17. To the free end of the arm 17 is pivoted one end of a link 18, the other end of said link being connected to the free end of a cam lever 19 fulcrumed at 20 to the frame of the cigar machine in connection with which the device is used. The cam lever 19 carries a bowl 21 which tracks in a groove 22 formed in one face of a cam 23 which is mounted on and driven by one of the main cam shafts of the cigar machine before referred to. The cam groove 22 is shaped to produce a rocking movement of the shaft 16; and when the shaft is rocked, the slides 10 and 11 are simultaneously reciprocated in their respective slideways.

To the upper end of the slide 11 is secured a yoke 24 having two upstanding ends 25—25 terminating in bunch shaping dies 26. To the upper end of the slide 10 is secured an arm 27 carrying a yoke 28 having depending ends 29 each terminating in a shaping die 30. The shaping dies 30 are complementary to the shaping dies 26; and when the shaft 16 is rocked in one direction, these complementary shaping dies are brought together by straight line movements. And when the shaft 16 is rocked in the opposite direction, the shaping dies will be moved apart also by straight line movements.

For the purpose of feeding a bunch into position to be acted upon by the shaping dies 26 and 30, there is provided bunch carrying means including a cradle 31 carried by two rods 32—32, the rear ends of which are joined by means of a yoke 33. The rods 32 are mounted to slide in suitable bearings formed in a bell-crank lever 34—35 fulcrumed at 36 to the support 7 before re-

ferred to. Passing through a suitable aperture in the yoke 33 is a screw 37 which is threaded into the arm 34 of the bell-crank lever 34-35. Surrounding the screw 37 and bearing against its head and against the yoke 33 is a spring 38 which normally holds the cradle in the position shown in Fig. 1. When, however, the bell-crank lever 34-35 is rocked on its fulcrum 36 to carry a bunch 10 into position to be shaped, the cradle 31 comes in contact with an adjustable stop 39 threaded into the support 7. The contact of the cradle with the stop brings the cradle to rest before the bell-crank lever comes to 15 rest, and further movement of the latter results in compressing the spring 8, as shown in Fig. 2. For the purpose of producing the rocking movement of the bell-crank 34-35, the arm 35 is pivoted to one end of a link 20 40, the other end of said link being pivoted to the free end of a cam lever 41 fulcrumed at 20 and provided with a cam bowl 42 engaging a groove 43 in the cam 23 before referred to.

25 For the purpose of aiding the cradle 31 in holding a bunch in proper position to be acted upon by the shaping dies 26 and 30, there is provided retaining means stationarily mounted on the support and engaging 30 one side of each of the dies, and movable retaining means intermittently engaging the opposite side of each of said dies to form a bunch end enclosing chamber which is reduced in size as the shaping dies move 35 toward each other. The stationarily mounted retaining means includes lugs 44-44 integral with the support 7, and to opposite ends of these lugs are screwed retaining walls 45-45, the operating surfaces of 40 which engage one side of each of the shaping dies 26 and 30. The arm 34 of the bell-crank 34-35 carries a yoke 46 which at each of its ends carries a retaining wall 47 complementary to the retaining wall 45 45 before referred to, and intermittently engaging the opposite side of the shaping dies 26 and 30.

When the parts are in the position shown in Figs. 1 and 3, a bunch is deposited in 50 the cradle 31. The cam lever 41 is then operated to convey the bunch into position to be acted upon by the shaping die, and when the bunch reaches this position the retaining walls 45 and 47 hold it in correct 55 position to be acted upon by the shaping dies 26 and 30. The latter then approach each other and effect the compression or shaping of the bunch ends; after which they retreat and the bell-crank 34-35 is swung 60 in the opposite direction to withdraw the shaped bunch from shaping position in order that it may be removed from the cradle.

What is claimed is:

1. A cigar bunch shaper comprising 65 bunch carrying means, and bunch com-

pressing means, a part of said compressing means being embodied in said carrying means.

2. A cigar bunch shaper comprising 70 bunch carrying means embodying an interrupted retaining wall, and bunch compressing means also embodying an interrupted retaining wall coacting with the carrying means wall when said compressing means is in action.

3. A cigar bunch shaper comprising 75 bunch carrying means adapted to engage the mid-section of a bunch, and bunch compressing means adapted to engage the ends 80 of the bunch, a part of said compressing means being embodied in said carrying means.

4. In a bunch shaper, the combination 85 with a support having two parallel slideways, of slides working in said slideways, coacting shaping dies carried by said slides, and means for simultaneously moving said slides in opposite directions.

5. In a bunch shaper, the combination 90 with a support having two parallel slideways, of slides working in said slideways, coacting shaping dies carried by the slides, retaining means mounted on said support and engaging one side of each of said dies, and means for simultaneously moving said 95 slides in opposite directions.

6. In a bunch shaper, the combination 100 with a support having two parallel slideways, of slides working in said slideways, coacting shaping dies carried by said slides, retaining means stationarily mounted on said support and engaging one side of each of said dies, movable retaining means intermittently engaging the opposite side of each of said dies, and means for simultaneously 105 moving said slides in opposite directions.

7. In a cigar bunch shaper, the combination 110 with a support having two parallel slideways, of slides working in said slideways, coacting shaping dies carried by said slides, means for simultaneously moving said slides in opposite directions, and means for positioning a cigar bunch between said dies.

8. In a cigar bunch shaper, the combination 115 with a support having two parallel slideways, of slides working in said slideways, two pair of shaping dies carried by said slides, means for simultaneously moving said slides in opposite directions, means for supporting a cigar bunch between said dies, and means for moving said supporting means in and out of position between said dies.

9. In a cigar bunch shaper, the combination 120 with a support having two parallel slideways, of slides working in said slideways, two pair of shaping dies carried by said slides, means for simultaneously moving said slides in opposite directions, retaining means stationarily mounted on said 125

support and engaging one side of each of said dies, means for positioning a bunch between said dies, and retaining means carried by said positioning means and intermittently engaging the opposite side of each of said dies.

10. In a cigar bunch shaper, the combination with a support having two parallel slideways, of slides working in said slide-
ways, coacting shaping dies carried by said slides, means for simultaneously moving said slides in opposite directions, and means mounted on said support for positioning a bunch between said dies.

11. In a cigar bunch shaper, the combination with a support having two parallel slideways, of slides working in said slide-ways, coacting shaping dies carried by said slides, cam-actuated means for simultaneously moving said slides in opposite directions, and cam-actuated means for positioning a bunch between said dies. 15 20

In testimony whereof, I have signed my name to this specification.

RUPERT E. RUNDELL.
